HORIZONTAL CENTRIFUGE

Pieter van Riel, Delft, Netherlands, assignor to
 Naamlooze Vennootschap Machinefabriek
 Reineveld, Delft, Netherlands, a manufac-
 turing company of the Netherlands

Application November 22, 1932, Serial No. 643,945
 In the Netherlands November 26, 1931

2 Claims. (Cl. 233—23)

A horizontal centrifuge comprises a basket, the bottom of which is secured to the horizontal shaft. In ordinary constructions of this type, the shaft is supported by two bearings on either side of the basket so as to be liable to bend or flex under the action of the weight of the basket. Moreover, the shaft of such a centrifuge has no freedom of translatory movement in addition to its rotation (as is the case with vertical centrifuges having the basket suspended from its spindle), so that it is very unfavourably loaded, especially if the charge is not exactly balanced.

My present invention, which more especially relates to a horizontal centrifuge having its basket directly driven by an electromotor, has for its object to avoid the aforesaid drawbacks. In accordance with my invention, one end shield of the motor is substantially conical, projects into a recessed portion of the bottom of the basket, and supports a bearing for the motor and basket shaft in such a manner that the centre of gravity of the basket is located within said bearing. With this construction the shaft is prevented from flexing, provided that the charge in the basket is not too unequally distributed.

In order that my invention may be more readily understood, I shall now proceed to describe the same with reference to the annexed drawing, which illustrates, by way of example, one embodiment thereof partly in elevation partly in vertical section.

The basket of the centrifuge is designated by 1. The bottom thereof has a deep recess 2 pro-
 35 vided with a hub member, to which the hori-
 zontal shaft 3 is secured. Said shaft is sup-
 ported by a roller bearing 4 carried by a bracket
 formed by a more or less conically shaped end
 shield 5 of the electromotor 6. Said bearing
 40 projects so far into the recess 2, that the centre
 of gravity Z of the basket is located centrally
 therein.

As shown, the presence of the recessed bottom portion 2 does not interfere with the provision of the usual supply pipe 7 and of a scraper 9, which is adapted to be reciprocated by means of an operating screw 8 provided with a chute 10 for guiding the material, scraped off from the inner wall of the basket, into a discharge nozzle 11.

What I claim is:

1. In a horizontal centrifuge, a basket hav- 10
 ing a horizontal axis and having a recessed por-
 tion in one wall closed against the interior of the
 basket, a power shaft passing into and through
 said recess to provide the axis of the basket, an
 electromotor of which said power shaft is the 15
 armature shaft, said motor having a casing in-
 cluding a conical end shield projecting into said
 recessed portion, and a bearing for the shaft
 supported by and within said shield, the center
 of gravity of the basket under all conditions 20
 being within said bearing.

2. In a horizontal centrifuge, a basket hav-
 ing a horizontal axis and having a recessed por-
 tion in one vertical wall thereof closed against
 the interior of the basket, a rigid frame, a motor 25
 having a casing rigidly secured and fixed with
 respect to said frame, said casing being extended
 to provide a conical portion projecting into but
 free of contact with the recessed portion of the
 basket, the armature shaft of the motor being 30
 extended through said conical end shield and
 through the wall of the recessed portion of the
 basket and removably fixed to said recessed por-
 tion, and an anti-friction bearing for the ar-
 mature shaft carried by said conical end shield, the 35
 arrangement of the parts being such that the
 center of gravity of the basket is within said anti-
 friction bearing under all conditions of opera-
 tion.

PIETER VAN RIEL.
